UNITED STATES PATENT OFFICE.

CHARLES L. NEDOMA, OF DETROIT, MICHIGAN, ASSIGNOR OF ONE-HALF TO FRANK M. HAWLEY, OF DETROIT, MICHIGAN.

CARBURETER.

1,222,236.

Specification of Letters Patent. Patented Apr. 10, 1917.

Application filed March 2, 1916. Serial No. 81,590.

To all whom it may concern:

Be it known that I, CHARLES L. NEDOMA, a subject of the Emperor of Austria-Hungary, and residing at Detroit, in the county of Wayne and State of Michigan, have invented a new and Improved Carbureter, of which the following is a specification.

This invention relates primarily to carbureters known as the automatic type in which the flow of liquid fuel is controlled by the action of an air controlled valve, and in which the size of the air passage in proximity to the point of fuel discharge is governed by the air velocity, although some of its features may be applied to carbureters of other types.

The high speed gasoline engines recently developed demand a fuel feeding apparatus that is efficient throughout a range of speed from 100 to 3000 or more revolutions per minute; and to accomplish the best results it is found that the air passage should be small at idling speed or at slow motor speed under full load, and should increase proportionately with the speed of the motor; also that the flow of fuel should be controlled during the whole range of motor speed, and should be applied to the air current in a series of small streams, rather than in one or more larger streams.

A primary object of the present invention is to provide an apparatus whereby the supply of air and fuel is regulated as above set forth, and also to provide means for increasing the discharge of liquid fuel upon the sudden opening of the throttle, said means being arranged to resist the sudden opening of the automatic valve and to cause the latter to close quickly when the throttle is closed. Other objects are to provide means for controlling the flow of fuel with reference to the movement of the automatic air valve during the whole range of operation whereby it may be either increased or decreased as the valve is lifted.

(The usual needle valve control provides means acting only one way, namely, to constantly increase the flow of fuel as the valve is lifted and at a rate that is not conducive to efficiency under certain conditions); to provide means for adjusting the carbureter with regard to atmospheric conditions without disturbing the adjustment in respect to range and rate of increase of flow of fuel; to provide an apparatus in which the fuel

is thoroughly atomized and in which the discharge of fuel from a plurality of jets is controlled at the discharge opening of the jets.

The several novel features comprised in the invention will be more fully described hereinafter and will be particularly pointed out in the subjoined claims.

In the embodiments of my invention shown, the movement of the automatic air valve is translated through cam means into a rotary movement of a tubular fuel control valve that sweeps over the discharge orifices of a series of very thin fuel discharge passages with which the device is provided; thus allowing a much finer adjustment of fuel delivery than would be the case if the air valve regulated the flow of fuel to the jets by means of a needle valve or metering pin. Because of the arrangement stated, a part or the whole of the motion of the air valve can be utilized to vary the flow of fuel, and the motion of the air valve in one direction may also be utilized to cause an alternating motion of the fuel valve, if desired, that is, a motion wherein the flow of fuel in respect to the flow of air, is first increased and afterward diminished, or the reverse.

In the drawings, Figure 1 is a longitudinal vertical section through a carbureter of the concentric float type in which my invention is embodied. Fig. 2 is a fragmentary elevation of the lower portion of the carbureter looking from the right in Fig. 1. Figs. 3, 4 and 5 are sections on the lines 3-3, 4-4 and 5-5 of Fig. 1. Fig. 6 shows in longitudinal cross section a series of cams of modified construction, the curves which they assume upon bending being indicated in dashed lines. Fig. 7 is a perspective view of the jet plate. Fig. 8 is a fragmentary perspective view of the upper end of the tubular fuel valve. Fig. 9 is a longitudinal section through a second embodiment of my invention taken on a line corresponding to the line 9-9 of Fig. 1. Fig. 10 is an elevation of the controlling cam looking from the right in Fig. 9. Fig. 11 is a similar view showing a cam of different contour.

Similar reference characters refer to like parts throughout the several views.

Referring to Figs. 1 to 4, inclusive, 1 indicates the body of the carbureter and in-

closed thereby is an annular float chamber, the supply of fuel for which is controlled by the float 2 and valve 3 in the usual way; adjacent the float chamber and preferably integral with the body is an auxiliary fuel chamber 4 that is connected to the float chamber by a duct or passage 5. The inner wall 6 of the float chamber forms an air passage 7, and is provided at its upper end 10 with the face 8 in which is located a circular fuel groove 9 that is supplied with fuel through the passages 10. The wall 6 is externally threaded upon its upper end to receive a ring 12 by which the annular jet plate 13, preferably of very thin sheet metal, is clamped in position. This plate has notches 14 in its inner periphery which communicate with the circular fuel groove 9 and open into the air passage, thus forming 15 narrow slot-like discharge jets for fuel. It will be observed that the faces of the wall 6 and the ring 12 are beveled or flared to form a valve seat, and that the jet plate lies at substantially right angles thereto. The 20 float chamber is provided with the cover 15 having an annular shoulder 16 that extends into sealing engagement with the ring 12 and converges upwardly as indicated at 17 to a restricted portion 18 across which a butterfly valve 19 is movable in the usual way. Below the float chamber the body of the carburetor is shaped to form a laterally turned warm air intake passage 20 (to which warm air may be supplied in any 25 suitable manner) and a similar cold air passage 21, the latter being controlled by a butterfly valve 22.

Conforming to the wall of the passage 7 is a rotatable tubular fuel valve 24 having a 30 flaring upper end 25 in which slots 26, corresponding substantially in number and size to the fuel jets, are formed; and arranged to approach and recede from the flaring end of the fuel valve is a conical air valve 28 of 35 the automatic type, the stem 29 of which extends vertically through a sleeve 30 interposed between it and the boss 29' on the lower wall of the air passages 20-21. Means, hereinafter described, are provided 40 for imparting rotary movement to the stem as the valve 28 rises, and this movement is transmitted to the fuel valve 24 through a cross-bar or spider 31, the ends of which slide in longitudinal grooves 32 in the inner 45 wall of the fuel valve. It will be understood that the cylindrical portion of the valve 24 moves practically without friction within the wall 6; the valve is provided on its lower end with an extension 33 including a 50 guide ring 34, and the sleeve 30 has a flange 35 upon its upper end and is threaded at its lower end to receive a nut 36 whereby the valve may be drawn downwardly to bring its flaring upper end into close relation to 55 the seat.

It will be observed that the flow of fuel is controlled directly at the outlet of the discharge openings; also that by the use of a proper movement reducing mechanism the total free opening through the fuel passages 70 may be regulated with extreme accuracy by and with reference to movement of the air valve and stem. A preferred mechanism for this purpose is constructed as follows:—Extending downwardly from the body is a 75 bracket or support 40, the lower horizontally-turned end 41 of which is threaded to receive a perforated nut 42 through which the valve stem is vertically slid able. The end 41 supports a collar 43 that includes a 80 socket 45 in which is received the preferably spherical end of an adjusting screw 46 that passes through the bracket 40 on a line offset from the center line of the valve stem. Rigid with the collar 43 and rising 85 therefrom is a bracket arm 48 through the upper end of which passes a second offset adjusting screw 49, similar to the screw 46, the spherical end of which engages with an upper collar 50 that is rotatably mounted on 90 the boss 29' on the body; and extending between the arms 52 and 53 that are formed, respectively, on the collars 43 and 50, is a flexible cam 54 (preferably a thin strip of metal) that serves as a guide for the cam 95 follower 55 and cam follower spring 56 which are pin connected to the valve stem at 58.

As indicated in Fig. 6, the cam 54 of uniform thickness may be replaced by cams 59, 100 the thickness of which varies, whereby, when the upper collar is adjusted in respect to the lower collar, the degree of curvature imparted to the cam may be made to vary at different points in the length thereof, 105 thus establishing a line of curvature which corresponds more nearly to the line upon which the particular engine will give maximum efficiency. Thus the rate of change in the supply of fuel may be made to vary at different points in the range of the engine. 110

Within the air passage the valve stem bears the ring collar 60, between the flanges of which is received the divided end 61 of a lever 62 which is pivoted in the body at 63 115 and has its other end divided and in engagement with the ring collar 64 that is carried on the lower end of a plunger rod 65. This rod extends upwardly through a guide sleeve 66 in the chamber 4 and is attached 120 to the tubular float bearing sleeve 68 to which the annular float 69 is secured in any desired manner, for example, by the flange 70 and ring 71. The cork float shown may be replaced by one formed of a hollow metal 125 shell.

Referring now to the embodiment of the invention shown in Figs. 9 and 10, and remembering that Fig. 9 is a section on a line corresponding to the line 9-9 130

of Fig. 1, it will be seen that with the exception of the cam mechanism and slight changes in form, the parts are the same as those of the first described form. The lower end 80 of the valve stem 81 is in this instance turned laterally and has its reduced extremity received in a slot 82 formed in a cam 83. The upper end 84 of the latter is received in an opening formed 10 in the wall of the air passage, and an arm 85, bent outwardly from the body of the cam, is rigidly secured to the lower end of an adjusting bolt 86 that passes through and fits closely in a bore 88 in a supporting 15 boss 89 on the carbureter body. A nut 90 determines the initial adjustment of the cam, and consequently the initial rate of flow, while the shape of the slot 82 controls the subsequent variation in the size of the 20 discharge orifice. As shown in Fig. 10, this slot may cause the free discharge openings to increase in size substantially in proportion to the movement of the air valve; in the form indicated in Fig. 11, the increase is first relatively rapid, then slow (or there may actually be a decrease), and then somewhat more rapidly. The shape of the cam will, of course, be modified to correspond to the needs of the particular engine 25 and service on which it is to be used.

Review of operation.—As the suction is applied to the air valve in the embodiment shown in Figs. 1 to 5, the valve rises, which, through the stem 29, cam follower 55—56 35 and cam 54, imparts rotative movement to the fuel valve 24 sufficient to vary the free opening through the very thin notches in the jet plate in accordance with the normal demands of the engine. This fuel, being delivered through the wall of the air passage and at substantially right angles to the thin sheet of air, is atomized more completely than is the case in ordinary constructions, and at the same time a more 40 accurate and reliable control of the varying rate of fuel supply is obtained than has been possible heretofore. Should the load be changed suddenly rather than gradually, the auxiliary fuel chamber and float provide 45 means for temporarily raising or lowering the level of the fuel in the float chamber in accordance with the demands of the engine under the particular condition, thus, among other things, preventing flooding.

55 The screw 46 affords means whereby the carbureter may be readily adjusted for altitude or weather without disturbing the range adjustment obtained through the screw 49.

60 The operation of the carbureter shown in the remaining figures is substantially the same with the exception that since the contour of the cam is of permanent character, the more ready range adjustment of the first construction is missing. It will be noticed

that the suction controlled valve is in this instance provided with grooves 95 by means of which air is directed in close relation to the ends of the jets when the engine is idling; in the embodiment first described the valve 70 is adjusted so as to have a slight clearance for the same purpose.

It is obvious that the details of construction may be varied within wide limits without departing from the spirit of the invention, and I do not, therefore, wish to be limited except as indicated by the subjoined claims.

I claim:

1. A carbureter comprising means for forming an air passage, a fuel reservoir, a plurality of fuel passages in communication with said reservoir, said passages opening into said air passage through the wall thereof, means for regulating the size of the free opening through the fuel passages, said means being operative at the discharge ends of said passages, a suction controlled air valve, and means whereby a movement of the air valve is made to control the opening 90 regulating means for the fuel passages.

2. A carbureter comprising means for forming an air passage, a fuel reservoir, a plurality of fuel passages in communication with said reservoir, said passages opening 95 into said air passage through the wall thereof at substantially the same level, means for regulating the free communication of the passages with the reservoir, said means being operative at the discharge end of said reservoir, a suction controlled air valve, said valve being shaped to deflect the air current over the ends of the fuel passages in a thin sheet, and means whereby a movement of the air valve controls the communication regulating means for the fuel passages.

3. A carbureter comprising means for forming an air passage circular in cross section, a fuel reservoir, a plurality of fuel passages in communication with said reservoir, said passages opening into said air passage through the wall thereof, a rotary fuel valve for regulating the free communication of the passages with the reservoir, a seat with which the fuel valve co-operates 115 a suction controlled air valve, and means whereby the air valve rotates the fuel valve to control the flow of fuel without approaching or receding from said seat.

4. A carbureter comprising means for forming an air passage circular in cross section, a fuel reservoir, a plurality of fuel passages in communication with said reservoir, said passages opening into said air passage through the outer wall thereof, a rotary tubular fuel valve having passages there-through corresponding to the fuel passages for determining the free opening through said fuel passages, a suction controlled air valve arranged to approach and recede from 125 130

- the discharge ends of the passages, and means whereby the air valve controls the rotary fuel valve.
5. A carbureter comprising in combination a tubular casing forming an air passage, a fuel jet leading to the air passage, a fuel valve conforming to the wall of the air passage for regulating the size of the free opening through the fuel jet, a suction controlled air valve, and means whereby a movement of the air valve is made to cause a simultaneous movement of the fuel valve whereby the size of the opening through the jet is determined.
10. 6. A carbureter comprising in combination a tubular casing forming an air passage, a fuel jet leading to the air passage, a fuel valve conforming to the wall of the air passage for regulating the flow of fuel from the jet, a suction controlled air valve, means whereby a movement of the air valve is made to cause a simultaneous movement of the fuel valve, said means including means whereby the movement of one of the valves with reference to the other may be regulated.
15. 7. A carbureter comprising in combination a tubular casing forming an air passage, a fuel jet leading to the air passage, a fuel valve conforming to the wall of the air passage for regulating the flow of fuel from the jet, a suction controlled air valve, means whereby a movement of the air valve is made to cause a simultaneous movement of the fuel valve at a reduced rate.
20. 8. A carbureter comprising in combination a tubular casing forming an air passage, a fuel jet leading to the air passage, a rotary tubular fuel valve conforming to the wall of the air passage for regulating the flow of fuel from the jet, a suction controlled air valve, and means whereby a movement of the air valve is made to cause a simultaneous rotary movement of the fuel valve at a different rate.
25. 9. A carbureter comprising in combination a tubular casing forming an air passage, a fuel jet leading to the air passage, a rotary tubular fuel valve conforming to the wall of the air passage for regulating the flow of fuel from the jet, a suction controlled air valve, and means whereby a movement of the air valve is made to cause a simultaneous rotary movement of the fuel valve at a different rate, said means including adjustable means whereby the movement of one of the valves with respect to the other may be varied.
30. 10. A carbureter comprising in combination a tubular casing forming an air passage, a fuel jet leading to said air passage, a tubular valve conforming to the wall of the air passage for regulating the flow of fuel from the jet, a suction controlled air valve, means connecting the valves for controlling the movement of the valves with respect to one another, said connecting means being adjustable to vary the movement of one of the valves with respect to the other, and additional means for adjusting the controlling means without disturbing the first mentioned adjustment whereby the richness of the fuel mixture may be varied to correspond to the weather or altitude.
35. 11. A carbureter comprising a tubular casing forming an air passage having an enlarged portion which constitutes a carbureting chamber and forming a valve seat between the enlarged portion and another portion, a flaring air-passage controlling valve movable toward and from the seat, fuel passages opening into the carbureting chamber along the valve seat, and a fuel valve movable over the discharge ends of the fuel passages to regulate the flow of fuel therefrom as the air passes into the mixing chamber.
40. 12. A carbureter comprising a tubular casing forming an air passage having an enlarged portion which constitutes a carbureting chamber and forming a valve seat between the enlarged portion and another portion, a flaring air-passage controlling valve movable toward and from the seat, fuel passages opening into the carbureting chamber along the valve seat, a fuel valve movable over the discharge ends of the fuel passages to regulate the flow of fuel therefrom as the air passes into the mixing chamber, and means whereby the air and fuel valve are caused to move in unison but at different rates.
45. 13. A carbureter comprising a tubular casing forming an air passage having an enlarged portion which constitutes a carbureting chamber and forming a valve seat between the enlarged portion and another portion, a suction controlled air valve movable toward and from the seat, fuel passages opening into the carbureting chamber along the valve seat, and a fuel valve movable over the discharge ends of the fuel passages to regulate the flow of fuel therefrom as the air passes into the carbureting chamber.
50. 14. A carbureter comprising a tubular casing forming an air passage having an enlarged portion which constitutes a carbureting chamber and forming a valve seat between the enlarged portion and another portion, a suction controlled air valve movable toward and from the seat, fuel passages opening into the carbureting chamber along the valve seat, a fuel valve movable over the discharge ends of the fuel passages to regulate the flow of fuel therefrom as the air passes into the carbureting chamber, and means for connecting the air valve and the fuel valve for causing the latter to be moved by the former but at a different rate.
55. 15. A carbureter comprising a tubular casing forming an air passage, a fuel passage leading to the air passage, a suction

- controlled air valve, said air valve having a stem, said stem being movable longitudinally of and rotatable about its own axis, a seat for a fuel valve, and a rotatable fuel controlling valve to which the rotary movement of the stem is imparted without causing the valve to approach or recede from the seat whereby the flow of fuel through the fuel passage is controlled.
16. A carbureter comprising a tubular casing forming an air passage, a fuel passage leading to the air passage, a suction controlled air valve, said air valve having a stem, said stem being movable longitudinally of and rotatable about its own axis, a rotatable fuel controlling valve to which the rotary movement of the stem is imparted whereby the flow of fuel through the fuel passage is controlled, and means whereby the rate of rotary movement of the fuel valve with respect to the rate of longitudinal movement of the valve stem is controlled.
17. A carbureter comprising a tubular casing forming an air passage, a fuel passage leading to the air passage, a suction controlled air valve, said air valve having a stem, said stem being movable longitudinally of and rotatable about its own axis, a rotatable fuel controlling valve to which the rotary movement of the stem is imparted whereby the flow of fuel through the fuel passage is controlled, and cam means whereby the rate of rotary movement of the fuel valve with respect to the rate of longitudinal movement of the valve stem is controlled.
18. A carbureter comprising a tubular casing forming an air passage, a fuel passage leading to the air passage, a suction controlled air valve, said air valve having a stem, said stem being movable longitudinally of and rotatable about its own axis, a rotatable fuel controlling valve to which the rotary movement of the stem is imparted whereby the flow of fuel through the fuel passage is controlled, cam means whereby the rate of rotary movement of the fuel valve with respect to the rate of longitudinal movement of the valve stem is controlled, and means whereby the cam means may be initially adjusted without disturbing the relative rates of movement of the air and fuel valves.
19. A carbureter comprising means for forming an air passage, a fuel reservoir, a plurality of fuel passages in communication with said reservoir, said passages opening into said air passage through the wall thereof, means for regulating the communication of the passages with the reservoir, said means being operative at the discharge ends of said passages, a suction controlled air valve, means whereby a movement of the air valve is made to control the communication
- regulating means for the fuel passages, and means for supplying an increased amount of fuel to the fuel passages upon a sudden opening movement of the air valve.
20. A carbureter comprising means for forming an air passage, a fuel reservoir, a plurality of fuel passages in communication with said reservoir, said passages opening into said air passage through the wall thereof, means for regulating the communication of the passages with the reservoir, said means being operative at the discharge ends of said passages, a suction controlled air valve, means whereby a movement of the air valve is made to control the communication regulating means for the fuel passages, and means for decreasing the amount of fuel supplied to the fuel passages upon a sudden closing movement of the air valve.
21. A carbureter comprising means for forming an air passage, a fuel reservoir, a plurality of fuel passages in communication with said reservoir, said passages opening into said air passage through the wall thereof, means for regulating the communication of the passages with the reservoir, said means being operative at the discharge ends of said passages, a suction controlled air valve, means whereby a movement of the air valve is made to control the communication regulating means for the fuel passages, and float means tending to return the air valve to passage closing position.
22. A carbureter comprising a tubular casing forming an air passage, a fuel passage leading to the air passage, a suction controlled air valve, said air valve having a stem, said stem being movable longitudinally of and rotatable about its own axis, a rotatable fuel controlling valve to which the rotary movement of the stem is imparted whereby the flow of fuel through the fuel passage is controlled, and float means connected to the valve stem, said means tending to return the air valve to passage closing position.
23. A carbureter comprising in combination a tubular member forming an air passage, a second tubular member in alinement therewith, a thin ring-like jet plate clamped between the members, said jet plate having a series of notches in its inner edge, said notches extending through the jet plate in a direction parallel to the axis of the tubular members, one of the members including means for supplying fuel to the notches, and a flaring suction controlled air valve arranged to approach or recede from the notches to regulate the width of the air current.
24. A carbureter comprising in combination a tubular member forming an air passage, a second tubular member in alinement therewith, a thin ring-like jet plate clamped between the members, said jet plate having

1 a series of notches in its inner edge, said
notches extending through the jet plate in a
direction parallel to the axis of the tubular
members, one of the members including
5 means for supplying fuel to the notches, a
flaring suction controlled air valve arranged
to approach or recede from the notches to
regulate the width of the air current, and a
tubular fuel valve movable across the
10 notches to regulate the flow of fuel there-
from.

25. A carbureter comprising in combina-
tion a tubular member forming an air pas-
sage, a second tubular member in alinement
15 therewith, a thin ring-like jet plate clamped
between the members, said jet plate having
a series of notches in its inner edge, said
notches extending through the jet plate in a
direction parallel to the axis of the tubular
20 members, one of the members including
means for supplying fuel to the notches, a
flaring suction controlled air valve arranged
to approach or recede from the notches to
regulate the width of the air current, and a
25 tubular fuel valve movable across the
notches to regulate the flow of fuel there-
from, said fuel valve being controlled by the
air valve.

26. A carbureter comprising a body form-

ing an air passage, a main fuel reservoir, a 30
fuel passage extending from the main fuel
reservoir to the air passage, an auxiliary fuel
reservoir in communication with the main
fuel reservoir, an air passage controlling
35 valve, a sleeve extending up into the auxil-
iary reservoir, a float rod passing through
the sleeve, a float operatively secured to the
rod, and means for transmitting a movement
of the float rod to the air passage control-
ling valve, whereby a tendency is exerted to 40
close the valve and to lower the level of the
fuel in the main reservoir when the air valve
suddenly closes.

27. A carbureter comprising a tubular cas-
ing forming an air passage having an en-
larged portion which constitutes a mixing
chamber, means for deflecting the air cur-
rent into the enlarged portion in a thin
stream the elements of which diverge from
one another, fuel passages opening into the 50
air passage at points opposite the air de-
flecting means, and a flaring fuel valve hav-
ing surface grooves parallel to the direction
of flow of the thin stream of air for regulat-
ing the flow of fuel at the discharge ends 55
of the fuel passages.

CHARLES L. NEDOMA.
